CLAIM

The ornamental design for a vehicle wheel spinner hub unit, as shown.

DESCRIPTION

FIG. 1 is a perspective view of a vehicle wheel spinner hub unit showing our new design;

FIG. 2 is a front elevation view thereof;

FIG. 3 is a rear elevation view thereof;

FIG. 4 is a right side elevation view thereof;

FIG. 5 is a top plan view thereof;

FIG. 6 is a bottom plan view thereof; and

FIG. 7 is a cross-sectional view thereof taken along line 7—7 in FIG. 3.
